JOIST ANCHORING BRACKET

Irvin D. Linehan, Chicago, Ill.

Application November 18, 1940, Serial No. 366,089

3 Claims. (Cl. 20—94)

This invention relates to joist brackets and more particularly to anchoring braces therefor, although certain features thereof may be employed with equal advantage for other purposes.

It contemplates more especially the provision of a joist anchoring brace or bracket that will effectively hold or solidly connect the joist to the foundation sill of a building structure to preclude movement influenced by high velocity winds, floods and severe storms.

It has been the practice for many years to support the joists upon the foundation sill without any special attaching expedients. The weight of the building structure serves to retain its position upon the foundation, but reliance upon weight alone is not entirely satisfactory in frame buildings subjected to high velocity winds, floods and severe storms. Even toe-nailing the joist to the foundation sill does not appreciably retard movement under such unusual strains and stresses so that it is a common occurrence for frame structures to sway, move and even become detached from their foundation under unusual climatic conditions.

This is especially true in cyclonic areas and when frame structures are subjected to floods. Under such conditions, frame structures have floated away or become dislodged from their foundation when the water mark exceeds the foundation height. This is primarily due to the fact that the frame structures are not anchored directly to the foundation or the foundation sill. While this condition is not apt to occur in brick structures, yet it would be highly desirable to anchor the joists therein to preclude any possible movement, sway or dislodgment.

It is worthy of note that joist anchors or braces may be advantageously used on the floors above the foundation, since the joists usually rest on a double plate which may be wood timbers nailed to the vertical struts. Rather than toe-nailing the joists to the double plate that supports the floors superposed above the foundation, joist anchoring brackets embodying features of the present invention can be advantageously used for this purpose.

This will eliminate defects due to severe strains such as high wind velocities and excessive weights constructed high above the foundation of the structure. Toe-nailing is not a very practical nor effective anchoring expedient. It has been resorted to in building structures merely to initially retain the joists in position prior to the application of the flooring as well as the walls to the frame. This type of anchor is not suf-

ficiently durable to preclude sway, movement or dislodgment of a building structure and is not intended to serve that purpose.

One object of the present invention is to provide an improved anchoring brace or bracket to securely tie building joists to the foundation or supporting plates.

Another object is to provide an improved building joist bracket of simple and inexpensive construction.

Still another object is to provide a joist bracket that will effectively serve as an anchor of a building structure to the foundation as well as superposed supporting plates, thereby securely anchoring the entire super-structure to the foundation.

A further object is to provide a simple and inexpensive joist bracket that serves as an anchor therefor to struts that extend downwardly therealong and to the corner posts comprising the framework of a building structure.

A still further object is to provide a simple and effective joist bracket that engages the entire upper edge of the joists to effect their attachment to the supporting sill or plates.

Still a further object is to provide a simple, inexpensive and durable joist anchoring bracket stamped or otherwise shaped from a single sheet of material to provide anchoring and retaining flanges to effectively connect joists to their supporting sills or plates.

Other objects and advantages will appear from the following description of an illustrative embodiment of the present invention.

In the drawings:

Figure 1 is a perspective view of a joist anchoring bracket embodying features of the present invention, dotted portions showing the alternate position of the top bracket extremity depending upon its position of use.

Figure 2 is a front view in elevation of confronting joist anchoring brackets utilized in two alternate forms to secure studs and joists to the supporting sill or plate.

Figure 3 is a fragmentary perspective view of building joists disposed adjacent to vertical studs conforming to the application of the brackets in alternate form corresponding to the showing in Figure 2.

Figure 4 is a development of the anchoring bracket shown in Figure 1.

Figure 5 is a fragmentary perspective view of building structures showing the application of the joist anchoring bracket to corners and intermediate struts of a building structure.

Figure 6 is a perspective view of a modified form of anchoring bracket embodying features of the present invention.

Figure 7 is a plan view of an anchoring bracket shown in Figure 6.

Figure 8 is a side view in elevation of the bracket shown in Figure 6.

Figure 9 is a development of the anchoring bracket shown in Figure 6.

Figure 10 is a fragmentary perspective view of a foundation portion of a building structure showing the joists anchored to the foundation sill.

The structure selected for illustration comprises, in this instance, a concrete foundation 10 which defines the basement space of a building structure and serves as a support therefor. Before the concrete foundation 10 sets, foundation sill anchoring bolts 11 are immersed in the soft concrete 10 so as to be rigidly held therein to afford the attachment of sills or plates 12-13 thereto. It is customary to provide a double sill or plate 12-13 which is ship-lapped to provide a corner joint as at 14-15 in conjunction with corresponding sills or plates 16-17 extending at right angles thereto to conform with the walls of the foundation 10.

It should be observed, however, that the double foundation sills or plates 12-13 are optional and that the number thereof is immaterial and depends largely upon the requirements of each building structure. In any event, however, the sills or plates 12-13 are anchored to the foundation 10 by the bolts 11 that have nuts and washers 18-19 secured to the upper extremity of the bolts 11. This facilitates and effectively secures the foundation sills 12-13 to the concrete foundation 10. The foundation sill or plate 13 supports the joists 20 which are uniformly spaced therealong to extend over the entire expanse of the floor area.

The joists 20 may have 16", 20" or 24" nails depending upon the dictates of commercial practice and the requirements of any installation. In order to effectively install the joists 20 to sill plates 13 that are horizontally spaced to conform with the length of the joists 20, angle brackets 21 are provided for this purpose. The joist anchor brackets comprise, in this instance, a sill plate member which is stamped or otherwise shaped from sheet steel or other suitable material to provide an angular webbed portion 22 having a rectangular base flange 23 bent therefrom to define an edge 24 to extend normally to the web 22.

An upstanding flange 25 extends from the bent edge 24 to terminate in an upper extreme edge 26 projecting beyond the highest point 27 of the web 22 to which it is joined by the edge 28. It should be noted that the lower extremity extreme edge 29 of the upwardly extending flange 25, projects beyond the web edge 24 to define a right angularly offset base flange 30 extending above the base flange 23 of the web 22 for overlapping contact therewith. The base flange 30 of the upwardly upstanding vertical flange 25 is joined thereto by the edge 31 which coincides with the extreme linear edge 32 of the base flange 23 constituting a part of the web 22. With this arrangement it will be observed that the bracket 21 is stamped from a single sheet of material to provide a rigid upstanding bracket having an overlapping horizontal base flange 23-30 and a vertical attaching flange 25, the flanges 25 and 23-30 being reinforced by the triangular web 22 extending therebetween.

In utilizing the joists 20 to rigidly support the vertical studs 33 or corner posts 34' for support

upon the foundation sill plates 13 or girders 34, the angle brackets 21 have their base flanges 23-30 resting on the horizontal sill plate or girder 34 for attachment thereto by means of a plurality 5 of suitable fasteners such as nails 35 projecting through apertures 36 and 37 in the overlapping base flanges 23-30. The vertical flange 25 is attached to the vertical surface of the studs 33 or corner posts 34' by attachment thereto by means 10 of any suitable fasteners such as nails 38 that project through a plurality of apertures 39 extending through the vertical flange 25.

In anchoring the joists 20 to the foundation sill plates 12-13 or to the girders 34, the vertical flange 25 is offset at an angle proximate to the upper extremity 26 thereof along a line coincident with the point of meeting 27 of a web edge 40 with the vertical flange 25 (Figure 1), thereby defining a horizontally offset flange 41 that engages the top surface 42 of the joists 20. Suitable fasteners such as nails 43 project through the top row of apertures 39 provided in the vertical flange 25. It is possible, therefore, to provide the angular bracket 21 to support the vertical stud 33 on one side and another angular bracket 21 with the horizontally offset top flange 41 anchored to the same girder 34 for attachment to adjacent joists 20 to provide a rigid and securely anchored vertical supporting stud 33 and horizontal joists 20 (Figures 2 and 3).

Where studs 33 are spaced from each other without any adjacent joists 20, oppositely disposed angle brackets 21 are anchored to the vertical studs 33 and the supporting horizontal girder 34 (Figure 5). Corner posts 34' are similarly supported and anchored against side-sway by providing two angle brackets 21 disposed at right angles to each other for anchored attachment to the intersecting girders 34 and the contiguous surfaces of the corner posts 34' (Figure 5). Similarly, the combined corner posts 34' with an adjacent joist 20 can be mounted and securely anchored in the manner described in connection with the arrangement shown in Figure 3.

Where joists 20 are disposed along the edges of the foundation sill plates 12 or 13 or both (Figure 10), the end joists 20 may be supported with an angle bracket 21 that has an upper horizontally offset flange 41 to effect engagement of the vertical as well as top horizontal surface thereof. Where flooring 44 is attached to the horizontal top surface 42 of the joists 20, the fasteners such as nails 43 are preferably driven through the flooring 44 for registry with the top row of apertures 39 in the vertical flange 25 that has been angularly offset to provide the flange 41. These nails will serve the dual purpose of anchoring the floor boards 44 and the angle brackets 21 to the joists 20. Thus, a single piece of angle bracket 45 of simple and improved construction has been provided that is adaptable to vertical studs 33 or corner posts 34, and joists 20 that may be spaced relative to each other or disposed in direct contact according to the requirements of any particular installation.

In the modified embodiment shown in Figures 6 to 9 inclusive, the double angle bracket 21' is combined as a unitary and integral unit. In this instance, there is provided oppositely disposed angular webs 22' which have two horizontally extending base flanges 23' joined thereto along the edges 24'. Vertical flanges 25' are disposed in spaced parallel relation to each other and terminate in an integral top flange 41' so as to define an inverted substantially U-shaped member

which will freely receive the joists 20' therein when the base flanges 23' are rigidly attached to the foundation sill plates 12-13 by resort to suitable fasteners such as nails 35'. Overlapping base flanges 30' are bent from the vertical flanges 25' to project in the direction of the base flanges 23' and contact therewith.

It will be observed that this structure affords the rigid vertical support of joists 20 for anchored attachment to foundation sill plates 12-13 or girders 34 without any possibility of vertical or side-sway in one direction or another. Apertures 36' and 39' are provided in the base flanges 23'-25', respectively, and also there are a plurality of apertures 39', in this instance two, provided through the top horizontal flange 41' that is common to the parallel spaced vertical flanges 25'.

The apertures 39' in the top flange 41' preferably receive the fasteners such as nails that project through the floor boards 44' or nails may be driven therethrough independent of the floor boards 44 depending upon the dictates of commercial practice. The double angle brackets 21' are stamped or otherwise shaped from a single piece of material to provide a rigid, inexpensive and exceedingly durable anchoring bracket for joists 20 that are secured to the foundation sill plates 12-13 or to girders 34.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. A joist or stud anchoring bracket comprising a vertical plate, an integral base flange offset horizontally relative to said vertical plate, there being apertures in said vertical plate and base

flange to receive attachment fasteners engageable with adjacent surfaces of building structures, and an angular web plate formed integral with and between said vertical plate and base flange, said vertical plate having a horizontally offset integral flange above said angular web to engage the top surface of a joist, there being apertures in said last named top flange to receive fasteners therethrough, and a flange formed integral with said vertical plate to overlap said base flange for attachment thereto.

2. A joist anchoring bracket comprising spaced vertical plates connected by a top flange to define a substantially inverted U-shaped joist receiving member, base flanges offset horizontally relative to said vertical plates, there being apertures in said vertical plates, top flanges and base flanges to receive attachment fasteners engageable with adjacent surfaces of building structures, angular web plates interposed between said vertical plates and base flanges, said base flanges being integrally joined to said angular web plates for extension therefrom, and integral flanges extending from and offset horizontally of said vertical plates to overlap said base flanges.

3. A joist anchoring bracket comprising spaced vertical plates connected by a top flange to define a substantially inverted U-shaped joist receiving member, base flanges offset horizontally relative to said vertical plates, there being apertures in said vertical plates, top flanges and base flanges to receive attachment fasteners engageable with adjacent surfaces of building structures, angular web plates interposed between said vertical plates and base flanges, said base flanges being integrally joined to said angular web plates for extension therefrom, and integral flanges extending from and offset horizontally of said vertical plates to overlap said base flanges, there being fastener apertures in said overlapping flanges to align with said apertures in said base flanges.

IRVIN D. LINEHAN.
